DESIGN FOR A STOCKING

Rose Carafa, Yonkers, N. Y.

Application January 25, 1940, Serial No. 89,700

Term of patent 7 years

To all whom it may concern:

Be it known that I, Rose Carafa, a citizen of the United States, residing at Yonkers, in the county of Westchester and State of New York, have invented a new, original, and ornamental Design for a Stocking, of which the following is a specification, reference being had to the accompanying drawing, forming part thereof.

The figure is a perspective view of a stocking showing my new design, the two rows of knots of the central element of the design continue around the rear part of the stocking.

I claim:

The ornamental design for a stocking, as shown and described.

ROSE CARAFA.
